(57) **CLAIM**

The ornamental design for a cutting insert for chip forming machining, as shown and described.

DESCRIPTION

FIG. 1 is a top, front and side perspective view of a cutting insert for chip forming machining showing my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a right side elevational view thereof; and,

FIG. 7 is a left side elevational view thereof.
